Patented Sept. 22, 1914.

UNITED STATES PATENT OFFICE.

VOLNEY T. MILLER, OF NESS CITY, KANSAS.

COMBINATION-RAZOR.

1,111,164.

Specification of Letters Patent. Patented Sept. 22, 1914.

Application filed June 27, 1913. Serial No. 776,086.

To all whom it may concern:

Be it known that I, VOLNEY T. MILLER, a citizen of the United States, residing in Ness City, in the county of Ness and State of Kansas, have invented a new and useful 5 Combination-Razor, of which the following is a specification.

My invention relates to improvements in a combination razor of the character specified, in which a movable blade arm and movable right and left guard arms are hung to a handle by a pin, common to all; a razor blade locking into the blade arm by a locking device at its outer end, thus making 10 a razor which may be used as an ordinary razor, and having a right and left safety guard, at the outer end of the safety guard arms, either or both of which may be closed into the handle or may be locked into the 15 blade arm thus converting the razor into a safety razor, the blade arm and safety arms closing into the handle which has a seat block at its outer end.

In the drawings:

25 Figure 1 is a side view of the razor showing safety devices locked in position. Fig. 2 is a side view of the razor showing the blade arm and safety arms. Fig. 3 is a cross section view of the blade arm and 30 safety extensions showing the safety extension locking devices. Fig. 4 is an end view of the blade arm and blade showing the blade locking device; Fig. 5 is a cross section view of the blade locking device; 35 Fig. 6 is a side view of the razor blade.

Similar numbers refer to similar parts throughout the several views.

The improved razor is composed of a blade holder 1, being two pieces of narrow 40 thin metal bound together parallel with each other by a rivet 15, the handle pin 14 and by the locking device 9. When the locking device is open the lips or fore end of the blade arm 1 are free to open above rivet 45 15 and thus release the blade 8. The post 12 is a vertical post fitting into the notch 17 in the razor blade thus forming part of the locking device for the blade 8. This post is fastened securely into one lip of the 50 blade arm 1 at such a distance from the closed locking device 9 as is the distance between the two notches 17. In the opposite lip of the blade arm 1 and directly opposite the lock post 12 there is a hole 55 through which the lock post passes freely, the outside being counter sunk so the lock

post 12 will pass through freely and not stick or bind.

The two lips of the blade arm are locked together by the locking device 9. This locking device consists of a short bolt, with a flanging head, hung in the outer end of one lip of the forearm 1, by a rivet or screw 19 near its bottom end, and is free to move forward or backward. Directly opposite in 60 the other lip of the blade arm 1 there is a slot 10, counter sunk on the outside, and in register with the lock bolt 9 and in which said bolt locks. When the razor blade 8 is in position in the blade arm 1 the lock 65 bolt 9 forms one of the binding posts for the notches 17 in the blade.

On the inside front side of each of the lips of the blade arm 1, and midway of the lock post 12 and the locking device 9, there 70 is a groove wide enough and deep enough to receive the teat 6 in the safety arms and slightly sloping outward at the back side to provide a lock for the slightly outward 75 projecting teat 6.

80 The guard arms 3 and 4 are thin stamped metal arms, hung to the handle of the razor on the pin 14 on opposite sides of the blade arm, and are so hung that they can either one or both, be shut into the handle or 85 locked onto the blade arm. They are so constructed that when the safety device is locked on to the blade arm the back side of the safety arm will lie flat against the outside of the razor arm, and parallel with 90 it, and the fore side of the safety extension 18 will lie flat against the razor blade. The difference in surface of the outside of the blade arm and the razor blade being met in the safety arm by a double opposed 95 angle thus making an offset which fits evenly the surface of the blade arm and the razor blade.

100 The safety extension 18 consists of an extension or widening of the guard arms 3 and 4 forming a plate that hugs the razor blade when locked in position on the blade arm. On the front side of these plates 18 are a series of teeth 5, being an elongation of the plates 18, spaced equally distant and parallel with each other, and at a suitable distance apart. The inside front side of such teeth being on a line approximately parallel with the cutting edge of the razor blade and sloping slightly forward toward their outside. These teeth are set on an angle, their 105 front end being forward of where they join 110

the guard plates 18 at approximately sixty degrees angle with the front edge of the guard plate 18, forming safety guards and at the same time guiding the razor slightly 5 forward in combination with its downward cutting motion, thus increasing the shaving qualities of the razor.

The teat 6 is a device that locks the safety guards 3 and 4 to the blade arm, the same 10 being stamped out of the angle in the safety arm. This teat 6 is in register with, and fits into the groove 7 in the blade arm and has a slightly outward angle toward its fore end, thus, when crowded into the groove 7, locking 15 the safety arms to the blade arm. The plates 18 are made slightly concave on the under side, the long way, and when it is desired to lock the safety devices 3 and 4 to the blade arm it is necessary for the operator 20 to press on the center of the safety plates and crowd the teat 6 into the groove 7. When the pressure is released the spring of the safety plate will seat the teat securely.

The blade consists of a thin sharp steel 25 blade in length approximately the distance between the lock post 12 and the locking device 9 and in width approximately equaling the distance from the back side of the blade arm 1 and the inside front side of the teeth 30 5, when the safety arms are locked in position on the blade arm. On each end of the blade are two notches 17 directly opposite each other and in which the lock post 12 and the locking device 9 fit when the blade 35 is in position in the blade arm.

The handle is an ordinary handle consisting of two strips of metal, celluloid, rubber, bone or other suitable material, placed parallel with each other and bound at the ends 40 by the pin 14 and a rivet or screw 16. The front side of the handle 13 is open to receive the safety arms 3 and 4 and the blade arm 1. All of these arms may be shut into the handle either with or without the razor 45 blade. To close the razor the safety arms are locked onto the blade arm and the three arms are then shut into the handle.

There is a seat block 2 between the outer ends of the handle strips 13 and this seat 50 block holds the outer ends of the handle

strips 13 sufficiently apart so that the handle will receive the arms, and is so constructed that it affords a seat for the closed arms. Through this seat block the rivet or screw passes.

I claim—

1. A combination razor of the character specified having a blade arm and right and left safety guard arms, the said three members being pivotally mounted at the back 60 end of an ordinary razor handle and having a locking device to lock either safety arm to the blade arm as desired, the said locking device consisting of concave safety extensions 18 and lock teats 6 and grooves 7. 65

2. A combination razor of the character specified having a blade arm 1 and safety arms 3 and 4, the said three members being pivoted to a common razor handle, the blade arm comprising two lips and having a blade 70 locking device 9 and lock post 12 and having grooves 7 in each lip of said blade arm, and the safety arms having safety extensions 18 on the back side of which are lock teats 6, all substantially as described. 75

3. A combination razor of the character specified having a blade arm 1 comprising two lips, and safety arms 3 and 4, the said three members pivoted to a common razor handle by a pin, the blade arm having lock 80 grooves 7 in each lip of said blade arm and the safety arms having safety extensions 18, on the back side of which, there are lock teats 6, and on the front edge a series of teeth 5, all substantially as described. 85

4. A blade arm comprising two long, narrow strips of metal held parallel with each other and having grooves on the under front side of each strip, in combination with a safety appliance of thin resilient metal, said safety appliance comprising two comb plates slightly concave on their underside the long way and having at their back sides lock teats to register with said grooves in the blade arm for the purposes set forth. 90
